UNITED STATES PATENT OFFICE

JOHN L. TAYLOR, OF WEST VIEW BOROUGH, PENNSYLVANIA

BARGE

Application filed November 23, 1928. Serial No. 321,382.

This invention relates to barges and similar craft, and has for its object the provision of a frameless all-steel barge having a self-supporting shell.

Heretofore, barges have been generally composed of a heavy framing including longitudinal and transverse members, and the shell was supported and secured to said framing. The framing of the barges was very heavy and costly and was of such nature that it interfered with the loading and unloading of the craft.

The present barge comprises a self-supporting shell and no framing is necessary. Therefore, such barge is of materially less weight, the initial cost is less and it may be more readily loaded and unloaded than barges in which a framework is employed.

In the drawings:

Figure 1 is a side elevation of a barge constructed in accordance with this invention.

Figure 2 is a plan thereof.

Figure 3 is a longitudinal sectional view of a portion of the barge, the other portion, being a duplicate construction, is not shown.

Figure 4 is a transverse sectional elevation.

Figure 5 is a fragmentary view illustrating an alternate corner construction.

Figure 6 is a partial longitudinal sectional view of a modified barge shell.

Figure 7 is a transverse sectional view taken on the line VII—VII of Figure 6.

Figure 8 is a plan of a deck barge constructed in accordance with this invention.

Figure 9 is a transverse sectional view taken on the line IX—IX of Figure 8.

Figure 10 is an enlarged fragmentary detailed view showing a section of barge shell constructed from rectangular tubes and plates.

Referring more particularly to the drawings, the numeral 2 designates tubular ribs which are preferably formed of lengths of pipe. The ribs 2 extend longitudinally of the barge and are spaced from each other.

Outer and inner walls 3 and 4, respectively, are mounted on the ribs 2 and are composed of a series of steel plates which are bridged across the spaces between the ribs and are welded thereto, as at 5. The walls 3 and 4

and ribs 2 form a self-supporting barge shell which is provided with air cells formed by the tubular ribs 2 and the spaces 6 between the ribs 2 and the inner and outer walls. The cellular structure of the barge shell decreases the weight of the shell and increases its buoyancy materially so as to increase its load carrying capacity. The load carrying capacity of the barge is also materially increased due to the absence of the framing ordinarily provided in barges.

Also, due to the novel construction, the inner and outer walls both present flat and substantially continuous surfaces,—the flat inner surface greatly facilitates the handling of the cargo while the flat outer surface reduces friction.

Transverse tubular ribs 8 are arranged at each end of the barge shell and welded to the inner side walls 4, and plates 9 are welded to the ribs 8 and to the walls 3 of the shell to form a water and air-tight bulkhead 10.

A plurality of traverses 14 are formed at suitable intervals intermediate the ends of the barge which extend lengthwise along the bottom from one side to the other of the barge. As shown, these traverses are formed of two inclined sides 15—15 which, together with the bottom of the barge, form water and air-tight compartments 16 of triangular cross-section, the bottom of the barge forming one side of the so formed triangle. The sides 15—15 are composed of plates welded to tubular transverse ribs 17 supported in notches formed in intermediate supporting plates 18. The ribs 17 are also welded to the inner side walls of the shell.

The barge is provided with the usual complement of towing-bitts 19 and 20 on its opposite sides and on each end thereof to provide means by which the barges are lashed or hitched together with the lines or ropes employed in making up a tow of barges, and the towing lines also are fastened to these bitts when the barge is being towed from place to place.

In Figures 6 and 7 I have shown a slightly modified form of barge in which the tubular ribs are arranged transversely of the double walled shell. In this construction two

series of ribs 21 and 22 are provided, the ribs 21 alternating with the ribs 22, and inner and outer walls 21^a and 22^a are supported on the ribs. The ribs 21 extend from the top edge of the barge on one side to the top edge of the barge on the other side, while the ribs 22 are of materially shorter length and extend across the bottom of the barge and only approximately half way up the side walls. 5 The walls and tubular supporting ribs 21 and 22 are all welded together so as to provide the air and water-tight compartments between the ribs, as described in the first or preferred construction above. 10

15 In Figures 8 and 9 I have shown a modified form of barge construction similar to the preferred construction described in the forepart of this application.

In this modified form of the invention, a 20 shell is formed like that of the preferred form composed of tubular ribs 25 arranged in spaced relation to each other and extending longitudinally of the barge, and inner and outer walls 26 and 27, respectively, 25 formed from plates welded directly to the ribs so as to form a hollow wall composed of water and air-tight compartments 28 from the spaces between the ribs and from the ribs themselves.

30 In this construction the bulkheads and triangular compartments are omitted, and a deck is formed over the entire shell. The deck, like the shell, is formed of longitudinally extending spaced tubular ribs 30 and 35 inner and outer walls 31 and 32 are formed by welding plates directly to the ribs. The interior of the barge is equally well adapted for liquid or solid cargo carrying and is divided by longitudinal and transverse partitions 33 and 34, respectively, into suitable 40 holds. The partitions 33 and 34 may be of any suitable construction but preferably are formed of spaced tubular ribs 35 and double walls 36 and 37 composed of plates welded 45 to the opposite sides of the ribs like the shell.

By constructing the shell, deck and partition walls all of tubular ribs and double walls, great strength, light weight and 50 greater buoyancy is obtained so that the load carrying quality of the barge is materially increased.

Suitable manholes 38 and hatches 39 are provided to permit access to the holds of the 55 barge.

In Figure 10 I have shown a fragmentary detail of a barge shell in which tubular ribs 40 are used to support inner and outer shell walls 41 and 42, composed of plates welded 60 to the longitudinal edges of the tubes, as at 43.

The double walled barges having tubular supporting ribs of this invention have many advantages over any barges heretofore constructed. The outer wall of said barges may

be punctured in every cell without sufficient loss of buoyancy to endanger the barge or cargo.

In the deck barges of Figures 8 and 9, the fact that the shell and deck are of cellular construction prevents the moisture gathering in the cargo holds from sweating and thereby insures a dry cargo. The cellular construction also prevents a rapid change of temperature which renders the barges particularly adaptable to refrigeration when the cargo needs to be kept cold, and also facilitates the heating of the barges when a cargo such as oil is carried and it is necessary to supply heat. 70

Another advantage is that the tubular ribs of the several barge constructions may be used as conduits for carrying refrigerating or heating mediums, thus leaving the interior of the barges entirely free from coils or pipes which would encroach upon the cargo carrying space. 80

The holds of barges constructed in accordance with this invention will be perfectly smooth, so as to facilitate cleaning, and the absence of all brackets and framing in the cargo holds leaves the entire cubic capacity free for a stowing cargo, which cargo will not be subject to damage from engagement with the brackets, etc., usually found in the cargo holds of ordinary barges. 90

Many modified constructions other than those shown and described may be made to adapt the barges constructed in accordance with the invention to various special uses without departing from the scope of my invention, as defined in the appended claims. 100

I claim:

1. A barge having its bottom, end and side walls composed of longitudinally extending tubular supporting ribs, said ribs being spaced transversely, and two series of plates welded to said ribs to form inner and outer spaced air-tight walls, said ribs separating the space between said walls into a series of air chambers. 105

2. A frameless barge comprising a shell composed of outer and inner spaced walls and tubular supporting members between and supporting said walls, said tubular supporting members extending longitudinally of said barge and being spaced transversely, said walls being composed of plates welded to said tubular members, and said tubular supporting members and the spaces between said tubular members forming air and water-tight compartments. 115

3. A frameless barge comprising a shell composed of outer and inner spaced walls and tubular supporting members between and supporting said walls, said tubular supporting members extending longitudinally of said barge and being spaced transversely, said walls being composed of plates welded to said tubular members, said tubular supporting 125

130

members and the spaces between said tubular members forming air and water-tight compartments, and air and water-tight bulkheads formed at each end of said shell.

5 4. A frameless barge comprising a shell composed of outer and inner spaced walls and tubular supporting members between and supporting said walls, said tubular supporting members extending longitudinally of said barge and being spaced transversely, said walls being composed of plates welded to said tubular members, said tubular supporting members and the spaces between said tubular members forming air and water-tight compartments, and air and water-tight bulkheads formed at each end of said shell, said bulkheads being composed of transverse tubular members extending between and welded to the inner side walls of said shell and plates supported on said transverse tubular members, said plates being welded to said tubular members and to said barge shell.

10 5. A frameless barge comprising a shell composed of outer and inner spaced walls and tubular supporting members between and supporting said walls, said tubular supporting members extending longitudinally of said barge and being spaced transversely, said walls being composed of plates welded to said tubular members, said tubular supporting members and the spaces between said tubular members forming air and water-tight compartments, air and water-tight bulkheads formed at each end of said shell, said bulkheads being composed of transverse tubular members extending between and welded to the inner side walls of said shell and plates supported on said transverse tubular members, said plates being welded to said tubular members and to said barge shell, and a plurality of transverse triangular-shaped air and water-tight compartments intermediate the ends of said barge, said compartments being formed by a plurality of vertically spaced transverse tubular members extending between and welded to the inner side walls of said shell, and plates welded to said tubular members and to each other and to the inner side and bottom walls of said shell.

15 6. A frameless barge comprising a self-supporting shell composed of outer and inner spaced walls and tubular supporting members between and supporting said walls, said tubular supporting members being spaced from each other, said walls being composed of plates welded to said tubular members, said tubular supporting members and the spaces between said tubular members forming individual air and water-tight compartments.

20 7. A frameless barge comprising a self-supporting shell composed of outer and inner spaced walls and tubular supporting members between and supporting said walls, said tubular supporting members being spaced from each other, said walls being composed of

25 plates welded to said tubular members, said tubular supporting members and the spaces between said tubular members forming individual air and water-tight compartments, and air and water-tight bulkheads formed at each end of said shell, said bulkheads being composed of transverse tubular members extending between and welded to the inner side walls of said shell and plates supported on said transverse tubular members, said plates being welded to said tubular members and to said barge shell.

30 In witness whereof, I have hereunto set my hand.

JOHN L. TAYLOR.
